PLEASANT BRADBURN AND WALTER CHAMBERS, OF MUNCIE, INDIANA.

RAIL-CLAMP.

1,272,767.

Specification of Letters Patent. Patented July 16, 1918.

Application filed April 16, 1918. Serial No. 228,937.

To all whom it may concern:

Be it known that we, PLEASANT BRADBURN and WALTER CHAMBERS, citizens of the United States, residing at Muncie, in the 5 county of Delaware and State of Indiana, have invented certain new and useful Improvements in Rail-Clamps, of which the following is a specification.

This invention is a rail clamp and has for 10 its principal object the production of a structure which will positively hold the rails from spreading or slipping from their correct positions when in use.

Another object of this invention is the 15 production of a rail clamp wherein a bar is provided and this bar is provided with rail receiving pockets adjacent its ends, thus permitting rails to be carried within the pockets, while clamping means is then applied for 20 holding the rails against removal from the pockets, thus causing the bar to hold the rails against spreading.

Another object of this invention is the 25 production of a rail clamp wherein the bar is provided with tenons at its ends, thus permitting clamps to be positioned over the tenons and fixedly secured thereto, whereby the clamp will be held in engagement with the rails mounted upon the bar for holding 30 the rails against accidental movement.

With these and other objects in view this 35 invention consists of certain novel combinations, constructions and arrangements of parts as will be hereinafter described and claimed.

One practical embodiment of construction and assembly of the present invention, with slight modifications thereof is hereinafter described, and illustrated in the drawing, in 40 which—

Figure 1 is a side elevation of the rail clamp in use.

Fig. 2 is an enlarged detail perspective view of one end of the bar of the rail clamp, 45 the clamping block being removed.

Fig. 3 is a slightly modified form of the invention illustrating how the structure may be used in connection with a steel tie, thus forming an abutment lug upon one side of 50 the rail pocket instead of providing a thickened abutment thereadjacent.

Referring to the accompanying drawing by numerals, it will be seen that the rail clamp comprises an elongated bar 1 having 55 thickened end portions 2.

Each thickened end 2 is provided with a transversely extending groove 3, thus forming a rail receiving pocket. The formation of the pocket therefore forms abutment shoulders 4 upon each side of the groove, 60 while the thickened end is further provided upon each side of the pocket and communicating with the shoulders 4 with spike receiving openings 5. Adjacent the outer ends 2 of the bar 1, are formed the longitudinally 65 extending tenons 6 projecting upwardly from the central portions of the thickened ends, as shown clearly in Fig. 2. These tenons 6 extend from the outer ends of the thickened ends 2 of the bar 1 and terminate adjacent 70 one abutment shoulder 4 of the pockets 3 formed in the thickened ends. It will further be noted that the tenons 6 are provided with openings 7 projecting therethrough for purposes to be hereinafter set forth. 75

The clamping blocks are similarly constructed, and each clamping block 8 has an internal pocket 9 formed therein as indicated in dotted lines in Fig. 1. The clamping block thus presented is also provided with a 80 rail engaging head 10 formed on its forward end, while it is provided at its rear end with a depending lug 11.

When this device is in use, it may be positioned upon a tie so as to allow the rails 85 12 to be placed in engagement therewith by the fitting of the rails within the pockets 3 although if so desired it may be placed in engagement with the rails independently of the tie and between a pair of adjacent ties. 90

The rails, as above specified, extend through the pockets 3 in the thickened ends 2 of the bar 1 and for this reason the base of the rails 12 will engage the abutment shoulders 4 formed contiguous to the pockets 3. The 95 clamping blocks are then brought into use, and are positioned over the tenons 6, for at this time the tenons 6 are received within the pockets 9 formed in the blocks 8, as illustrated in Fig. 1. Bolts or other securing 100 elements 13 are then passed through the blocks 8 and through the openings 7 formed in the tenons 6, thus firmly connecting the clamping blocks 8 upon the tenons. In this way the blocks will be held to the thickened 105 ends 2 of the bar 1 and as the rail engaging heads 10 of these blocks engage the base, the web and also the tread of the rails, it is obvious the rails will be firmly held in the pockets of the bar. Therefore, the bar being 110

- of an elongated construction it will positively hold the rails against spreading or springing from their correct positions. It will be noted that the depending lugs 11 of the blocks will fit upon the ends of the thickened ends 2 of the bar 1 and will further assist in steadyng the clamping blocks and holding the same in their correct positions.
- 10 By referring to Fig. 3, a slightly modified form of the device is disclosed wherein the structure is intended to be used in connection with a metal tie 14 which may have an abutment lug 15 struck therefrom or formed thereon to engage the base of the rail 16. The tenon 17 is formed integral with the tie 14. The clamping blocks 18 are positioned over the tenon in the manner similar to which the first form is used and then suitable securing means is passed through the blocks and the tenon for securing these elements together to bear upon the rail and hold the same against displacement in the manner similar to which the preferred form is used. The principal difference in the modified form and the preferred form resides in the formation of an abutment lug instead of a thickened portion as used upon the bar of the preferred form of the invention.
- 15 It is obvious that detail changes may be made in the construction of the present invention, without departing from the spirit of the device and for this reason it is intended to include all such modifications as properly come within the scope of the invention as claimed.
- What is claimed is:
1. In a rail clamp of the class described, the combination of a bar having rail receiving pockets adjacent its ends, tenons formed upon said bar and extending to said pockets, clamping blocks having internal pockets formed therein, each block having a rail engaging head at one end and a depending lug at the opposite end thereof, said heads being adapted to engage rails fitting within said pockets, while said lugs engage the ends of said bar, thus steadyng said blocks, and securing means passing through said blocks and said tenons for holding said blocks in set position.
  2. In a rail clamp of the class described, the combination of a bar having receiving pockets adjacent its ends, clamping blocks, each block having a rail engaging head at one end and a depending lug at the opposite end thereof, said heads being adapted to engage rails fitting within said pockets, while said lugs engage the ends of the bar, thus steadyng said blocks, and means for holding said blocks in set positions upon said bar.
  3. In a rail clamp of the class described, the combination of a bar, tenons formed on said bar, clamping blocks having internal pockets formed therein, each block having a depending lug at its outer end, said block being adapted to engage a rail resting upon said bar, while the lug engages the outer end of the bar, thus being steadyed, and securing means passing through said blocks and said tenons for holding said blocks in set positions.
  4. In a rail clamp of the class described, the combination of a bar having rail receiving pockets adjacent its ends, tenons formed on said bar and extending to said pockets, clamping blocks, each block having a rail engaging head at one end and a depending lug at the opposite end thereof, said heads being adapted to engage rails fitting within said pockets, while said lugs engage the ends of said bar, thus steadyng said blocks, said blocks engaging said tenons, and means for holding said blocks in set positions.
  5. In a rail clamp of the class described, the combination of a bar including means for engaging the base of rails for holding the rails against side shifting, tenons formed on said bar, clamping blocks, each block having a rail engaging head at one end and a depending lug at the opposite end thereof, said heads being adapted to engage rails fitting within said pockets, while said lugs engage the ends of said bar, thus steadyng said blocks, said blocks engaging said tenons, and means for holding said blocks in set positions.
  6. In a rail clamp of the class described, the combination of a bar having receiving pockets adjacent its ends, clamping blocks having depending lugs at their outer ends, said blocks being adapted to engage rails fitting within said pockets, while said lugs engage the ends of the bar, thus steadyng said blocks, and means for holding said blocks in set positions upon said bar.
  7. In a rail clamp of the class described, the combination of a bar, tenons formed on said bar, clamping blocks having internal pockets formed therein, each block having a depending lug at its outer end, said block being adapted to engage a rail resting upon said bar, while the lug engages the outer end of the bar, thus being steadyed, and securing means passing through said blocks and said tenons for holding said blocks in set positions.
  8. In a rail clamp of the class described, the combination of a bar having rail receiving pockets adjacent its end, tenons formed on said bar and depending from said pockets, clamping blocks having depending lugs at their outer ends, said blocks being adapted to engage rails fitting within said pockets, while said lugs engage the ends of said bar, thus steadyng said blocks, said blocks engaging said tenons, and means for holding said blocks in set positions.
  9. In a rail clamp of the class described,

the combination of a bar including means for engaging the base of rails for holding the rails against side shifting, tenons formed on said bar, clamping blocks having depending lugs at their outer ends, said blocks being adapted to engage rails carried by said bar, while said lugs engage the ends of said bar, thus steadyng said blocks, said blocks engaging said tenons, and means connecting

said blocks and said tenons for holding said 10 blocks in set position.

In testimony whereof we affix our signatures in presence of two witnesses.

PLEASANT BRADBURN.
WALTER CHAMBERS.
